UNITED STATES PATENT OFFICE.

GEORGE H. BARBOUR AND MERRILL B. MILLS, OF DETROIT, MICHIGAN,
ASSIGNORS TO THE MICHIGAN STOVE COMPANY, OF SAME PLACE.

MAGAZINE DRUM-STOVE.

SPECIFICATION forming part of Letters Patent No. 267,769, dated November 21, 1882.

Application filed April 4, 1882. (No model.)

To all whom it may concern:

Be it known that we, GEORGE H. BARBOUR and MERRILL B. MILLS, of Detroit, county of Wayne, State of Michigan, have invented a new and useful Improvement in Magazine Drum-Stoves; and we declare the following to be a full, clear and exact description of the same, such as will enable others skilled in the art to which it pertains to make and use it, reference being had to the accompanying drawings, which form a part of this specification.

Our invention consists of combinations of devices and appliances hereinafter specified, and more particularly pointed out in the claims.

15 In the drawings, Figure 1 is a view in elevation of the magazine-section of a magazine-stove embodying our invention. Fig. 2 is a cross-section of the same.

Heretofore in the manufacture of heating-stoves it has been customary to make the outer shell of the magazine-section of cast-iron, then to ornament its exterior by plating and polishing the same with nickel or other non-oxidizable metal. In use, however, it 25 was developed that the heat would soon dis-color and tarnish the said plated surfaces. It has been remedied to a considerable extent by making the outer shell of the magazine-section separate from the wall of the stove, so as to 30 admit a current of air at the base of this shell and permit the latter to circulate up between the wall of the stove and this exterior shell upon the magazine-section, there being provided openings at the top for the exit of the 35 heated air into the room. It has been difficult, however, to impart to the cast-metal surface a very high degree of polish, and as a result the surface is not so attractive as it would otherwise be.

40 It is the object of this invention to produce a shell for the magazine-section which shall be capable of receiving a very high degree of polish. To this end we propose to make the shell with an exterior surface-shell of rolled or spun metal, preferably of brass or copper, suscep-tible of receiving a very high polish, and to plate the said metal with nickel, silver, or gold. A metal of this character, when so plated, has a brilliant luster which it is impos-sible to impart to a ground and polished sur-

face of cast-iron. This entire surface-shell may be made of one piece of such metal, riveted or brazed at the back, and be made plain, or ornaments may be rolled upon them, and this may be slipped over a cast-iron supporting-shell. Instead of making this exterior surface-shell in a single piece, it may be made in a series of bands of greater or less breadth, all of which may be ornamented; or some may be ornamented and others plain, said bands being united by rivets or by brazing, or by a lap-joint, so as to make any band continuous; or, the bands being narrow, they may be spun into shape from a single piece and without joint. These different bands may be so shaped as to engage at their edges as ordinary stove-pipe joints engage with each other. So, also, instead of being superposed upon a cast metal shell, it is entirely practicable, and we propose generally to superimpose it upon an inner shell 55 of sheet-iron, which is at once light, cheap, and easily shaped to fit into adjacent parts—as, for instance, the metallic cup at the top of the stove and a metallic ring at the base of the magazine-section.

75 In the drawings, the figures of which represent the upper portion of a magazine-stove, A indicates the ordinary magazine-section of the stove-shell, F being the magazine.

B is a separate removable shell about the 80 magazine-section, an air-space, b, being be-tween it and said section.

C is a metallic ring, which rests upon a per-forated flange projecting from the magazine, and forms the bottom of this removable sec-tion, and D D' a top frame which finishes the 85 upper end of the section and unites it to the top of the stove. The sections D and D' are suitably perforated to facilitate the circulation of air.

90 E represents the exterior surface-shell. It consists, as above explained, of one or more plain or plain and ornamental bands, e.

The shell B, surface-shell E, and support-ing-ring and frame may be detached readily 95 from the magazine-section, thus making this ornamental feature portable, so that it can be stored away as silver-ware is stored until the following season.

We do not confine ourselves solely to the 100

use of this spun or rolled metal upon the magazine-section; but any other part of the stove—
as, for instance, the surfaces composing the
top, or those corresponding with the ordinary
5 bright bands about the stove—may be thus
made of spun metal shaped to conform to the
casting, and so laid over the latter and turned
at its edges to hold it secure.

What I claim is—

- 10 1. A stove-shell having an exterior surface-shell of spun or rolled metal, which has its exterior surface plated with a different metal, substantially as described.
- 15 2. A stove-body having a surrounding shell separated therefrom by an air-space, and provided with an exterior surface-shell of spun or rolled metal, plated on the outside with a different metal, substantially as described.
- 20 3. A stove-shell having an exterior surface-shell composed of two or more bands of spun or rolled metal, the exterior faces of which are plated with a different metal, substantially as described.
- 25 4. The combination, with a stove-body, of

two removable projecting rings or flanges, and a 25
separate shell supported between said rings or
flanges and provided with an exterior surface-
shell of spun or rolled metal plated on its out-
side with a different metal, substantially as
described.

30 5. The combination, with a stove-body, of
two projecting rings or flanges perforated for
the passage of air, and a separate shell sup-
ported by said rings or flanges, and separated
from the stove-body by an air-space which is 35
in communication with the perforations of said
rings or flanges, said separate shell being pro-
vided with an exterior surface-shell of spun or
rolled metal, plated on its outside with a dif-
ferent metal, substantially as described.

40 In testimony whereof we sign this specifica-
tion in the presence of two witnesses.

GEORGE H. BARBOUR.
MERRILL B. MILLS.
